UNITED STATES PATENT OFFICE

FRANCES A. JACOBS, OF CHICAGO, ILLINOIS, ASSIGNOR TO THE STERLING COMPANY, OF CHICAGO, ILLINOIS, A CORPORATION OF WEST VIRGINIA

DESIGN FOR A DRESS

Application filed March 26, 1931. Serial No. 39,246. Term of patent 7 years.

To all whom it may concern:

Be it known that I, FRANCES A. JACOBS, a citizen of the United States, residing at Chicago, in the county of Cook and State of Illinois, have invented a new, original, and ornamental Design for a Dress, of which the following is a specification, reference being had to the accompanying drawings, forming a part thereof.

Fig. 1 is a front elevational view of a dress constituting my design.

Fig. 2 is a rear elevational view on reduced scale of the dress shown in Fig. 1.

I claim:

The ornamental design for a dress as shown. In witness whereof, I hereunto subscribe my name this 26 day of March, 1931, at Chicago, Illinois.

FRANCES A. JACOBS.
